UNITED STATES PATENT OFFICE.

JACOB WALTER AND HENRY E. WALTER, OF BUFFALO, NEW YORK.

DESIGN FOR A CLAMP MEMBER.

SPECIFICATION forming part of Design No. 33,026, dated July 31, 1900.

Application filed July 9, 1900. Serial No. 23,052. Term of patent 3½ years.

To all whom it may concern:

Be it known that we, JACOB WALTER and HENRY E. WALTER, citizens of the United States, residing at Buffalo, in the county of Erie and State of New York, have invented and produced a new and original Design for Clamp Members, of which the following is a specification, reference being had to the accompanying drawings, being a part thereof.

10 This design relates to the configuration of the pivoted members of clamps which are employed for holding a number of parts together in gluing or brazing the same.

In the accompanying drawings, Figure 1 is 15 a side elevation of a clamp member embodying our design. Fig. 2 is a perspective view of the member viewed from its inner side.

Like letters of reference refer to like parts in both figures.

20 As shown in the drawings, the leading feature of our design consists of a curved or outwardly-bowed jaw A, having at its front end a forwardly-extending lip a, a handle B, extending downwardly and outwardly from the 25 lower end of said jaw, and a cup-shaped boss

C, of approximately-circular form, arranged at the junction of the jaw A and the handle B and extending inwardly therefrom. This boss is arranged on one side of the longitudinal center line of the jaw A and the handle B. 30

d is a curved or segmental groove arranged at the inner side of the cup-shaped boss C, and d' a lug or teat arranged at the inner edge of the boss opposite said groove.

e is a recess arranged in the lower portion 35 of the wall or rim of the cup-shaped boss, and f is an opening formed centrally in the bottom of the cup.

g represents lugs arranged on the inner side of the handle B. 40

What we claim is—

The design for a clamp member, substantially as herein shown and described.

Witness our hands this 16th day of May, 1900.

JACOB WALTER.
HENRY E. WALTER.
